PIPE REPAIR SLEEVE

Elme L. Condra, Long Beach, Calif.

Application August 3, 1950, Serial No. 177,415

5 Claims. (Cl. 166—11)

1

This invention relates to a pipe repair sleeve whereby an annular packing may be set within a pipe and on each side of a hole or crack in the pipe.

An object of my invention is to provide a novel pipe repair sleeve which may be run into a deep well, such as an oil well, and, after the sleeve is in position each packing may be set successively, thus packing off on both sides of a possible hole or crack in the pipe.

Still another object of my invention is to provide a pipe repair sleeve of the character stated, in which the operating mandrel can be removed leaving a tubular sleeve or pipe section in the well.

Still another object of my invention is to provide a novel pipe repair sleeve in which the spaced annular packings can be set or expanded by rotation of the operating mandrel in the tool.

A feature of my invention resides in the means whereby the operating mandrel can be shifted longitudinally to cause first one annular packing and then the other to be compressed or expanded, this compression or expansion occurring by reason of rotation of the operating mandrel.

Other objects, advantages and features may appear from the accompanying drawing, the subjoined detailed description and the appended claims.

In the drawing:

Figure 1 is a side elevation of my pipe repair sleeve with parts broken away to show interior construction, and showing one annular packing expanded.

Figure 2 is a view similar to Figure 1, but showing both of the annular packings expanded.

Figure 3 is a sectional view taken on line 3—3 of Figure 1.

Figure 4 is a sectional view taken on line 4—4 of Figure 2.

Referring more particularly to the drawing, the numeral 1 indicates the pipe, such as casing in a well, and this casing has a hole or crack 2 therein, and this hole is at a considerable distance below the surface of the ground.

My pipe repair sleeve consists of an outer tubular assembly 3, which is formed of the following parts:

A bottom shoe 4 has a plurality of spring fingers 5 attached to the lower end thereof and expandable outwardly to engage the pipe 1. The spring fingers hold the shoe 4 against rotation in the pipe 1 when the tool is being set, as will be subsequently described. A collar 6 is secured to the lower end of the pipe 7 and is internally threaded, as shown at 8, to receive the threads

9 on the upper end of the shoe 4. An annular packing 10 is mounted on the shoe 4 adjacent its upper end, and this packing rests on a shoulder 11 on the shoe. A ring 12 is positioned between the collar 6 and the top of the packing 10, so that when the collar 6 threads downwardly on the threads 9, the ring 12 will engage the top of the packing 10, compressing and expanding this packing against the pipe 1.

10 A second collar 13 screws on to the upper end of the pipe 7 and also on to the lower end of a sleeve 14. A second annular packing 15 surrounds the sleeve 14 and rests on a bottom shoulder 16. The sleeve 14 threads into the lower end of a top sub 17, and a ring 18 is positioned between the bottom of the sub 17 and the top of the packing 15. Thus, when the sleeve 14 threads upwardly into the sub 17, the ring 18 will press against the top of the packing 15, thus compressing and expanding this packing against the pipe 1.

15 A J slot 19 is cut in the sub 17 and receives a drive pin 20 protruding from the mandrel 21. This mandrel depends from the drill pipe 22, which is run into the pipe 1 from the surface. A key 23 is mounted in the side of the mandrel 21 and is pressed outwardly by the springs 24. In one position of the mandrel 21 this key enters a notch 25 in the collar 13, thus connecting the mandrel and causing these parts to rotate when the drill pipe 22 is rotated. When the mandrel 21 is pushed downwardly, as shown in Figure 2, the key 23 will be pressed inwardly and will move out of the notch 25 and thereafter the collar 13 and attached parts do not rotate with the mandrel 21.

20 In operation, the parts are first assembled substantially as shown in Figure 1, except that the packing 10 is not expanded, that is, the entire tubular assembly 3 hangs from the pin 20, which is positioned in the J slot 19, as shown in Figure 1. The tool is now lowered into the pipe 1 to a point where the packing 10 will be below the hole 2 and the packing 15 will be above this hole. The depth of the hole 2 is obtained with a well known type of tool, such as a fluid pressure tool shown in Patent No. 2,344,120. The spring fingers 5 are now holding the shoe 4 against rotation and by rotating the drill pipe 22 this torque will be imparted to the sub 17 through the pin 20, and also the key 23 which rests in its notch or groove 25. Thus, the collar 6 will screw downwardly on the threads 9 to force the ring 12 against the top of the packing 10 and expand this packing against the pipe 1. The lower packing is now set. 25 By lowering the drill pipe 22, the key 23 will

move out of its slot 25 to the position shown in Figure 2. Also, the pin 20 will now engage the lower part of the J slot 19 and, therefore, rotation of the drill pipe 22 will only rotate the sub 17. The balance of the tubular portion of the sleeve will remain stationary. Rotation of the sub 17 will screw this sub downwardly on to the threads of the sleeve 14, thus compressing the packing 15 against the pipe 1 and thereby sealing off both above and below the hole 2. The drill pipe 22 and its attached mandrel 21 can now be pulled upwardly to the surface, since the pin 20 can be pulled out of the open end of the J slot 19. This leaves a tubular structure in the well through which bits, drill pipe, etc., can pass, and also the hole 2 has been effectively stopped off by the packing 10 and 15.

Having described my invention, I claim:

1. A pipe repair sleeve, a drill pipe on which said sleeve is mounted, said pipe being movable into a well, the sleeve consisting of an outer tubular assembly comprising a sub, a center section, and a shoe, said sub being threaded into the top of the center section, and said shoe being threaded into the bottom of the center section, a packer mounted on the sub, a second packer mounted on the shoe, each of said packers being compressed against the center section on rotation of the repair sleeve, spring fingers on the shoe engaging the pipe, a drive mandrel mounted on the drill pipe and extending into said tubular assembly, and spring detent means engaging said center section whereby the tubular assembly is rotated with said mandrel.

2. A pipe repair sleeve, a drill pipe on which said sleeve is mounted, said pipe being movable into a well, the sleeve consisting of an outer tubular assembly comprising a sub, a central section, and a shoe, said sub being threaded into the top of the center section, and said shoe being threaded into the bottom of the center section, a packer mounted on the sub, a second packer mounted on the shoe, each of said packers being compressed against the center section on rotation of the repair sleeve, spring fingers on the shoe engaging the pipe, a drive mandrel mounted on the drill pipe and extending into said tubular assembly, a key mounted on the side of the mandrel, springs pressing said key outwardly, said center section having a recess therein to receive said key, said key being movable into and out of said recess on longitudinal movement of the mandrel relative to the tubular assembly.

3. A pipe repair sleeve, a drill pipe on which said sleeve is mounted, said pipe being movable into a well, the sleeve consisting of an outer tubular assembly comprising a sub, a central section, and a shoe, said sub being threaded into the top of the center section, and said shoe being threaded into the bottom of the center section, a packer

mounted on the sub, a second packer mounted on the shoe, each of said packers being compressed against the center section on rotation of the repair sleeve, spring fingers on the shoe engaging the pipe, a drive mandrel mounted on the drill pipe and extending into said tubular assembly, a key mounted on the side of the mandrel, springs pressing said key outwardly, said center section having a recess therein to receive said key, said key being movable into and out of said recess on longitudinal movement of the mandrel relative to the tubular assembly, said sub having a J slot therein and a pin extending from the mandrel into said J slot.

4. A pipe repair sleeve and a drill pipe on which said sleeve is mounted, said drill pipe being movable into a well, the sleeve consisting of an outer tubular assembly comprising a top sub, a center tubular section, and a bottom shoe, said sub being threaded onto the top of the center section, said shoe being threaded onto the bottom of the center section, a packer mounted on the sub and positioned between said sub and the top of the center section, a second packer mounted on the shoe and positioned between the shoe and the bottom of the center section, spring fingers on the outside of the shoe, a mandrel mounted on the drill pipe and projecting into the tubular assembly, a spring detent on the mandrel engaging the said center section of the tubular assembly to rotate the same, and inter-connecting drive means projecting from the mandrel and engaging said sub.

5. A pipe repair sleeve and a drill pipe on which said sleeve is mounted, said drill pipe being movable into a well, the sleeve consisting of an outer tubular assembly comprising a top sub, a center tubular section, and a bottom shoe, said sub being threaded onto the top of the center section, said shoe being threaded onto the bottom of the center section, a packer mounted on the sub and positioned between said sub and the top of the center section, a second packer mounted on the shoe and positioned between the shoe and the bottom of the center section, spring fingers on the outside of the shoe, a mandrel on the drill pipe and projecting into the tubular assembly, a spring detent mounted on the side of said mandrel, said center section of the tubular assembly having a recess therein to receive said detent, said sub having a J slot therein and a pin projecting from said mandrel into the J slot.

ELMO L. CONDRA.
